CLAIM

The ornamental design for a toy kangaroo, substantially as shown and described.

DESCRIPTION

FIG. 1 is a front perspective view of a toy kangaroo showing our new design;

FIG. 2 is a right-side elevational view thereof;

FIG. 3 is a rear elevational view thereof; and

FIG. 4 is a bottom plan view thereof.

In FIGS. 2—4 the bellows member and the connecting tube have been shown in fragment for ease of illustration.
